UNITED STATES PATENT OFFICE.

RICHARD K. HOHMANN, OF BELVIDERE, ILLINOIS.

SEWING-MACHINE.

1,150,368.

Specification of Letters Patent. Patented Aug. 17, 1915.

Application filed September 19, 1914. Serial No. 862,588.

To all whom it may concern:

Be it known that I, RICHARD K. HOHMANN, a citizen of the United States, and resident of Belvidere, Boone county, State 5 of Illinois, have invented certain new and useful Improvements in Sewing-Machines, of which the following is a specification.

This invention relates to sewing machines and more particularly to improvements in 10 the shuttle mechanism whereby bobbins containing two or more times as much thread as the ordinary bobbin may be used. The invention has particular reference to tension means for the thread and it is one of the objects to provide a tension device which will produce a substantially uniform tension on 15 the thread irrespective of the size of the thread or the amount of thread on the bobbin.

20 The novel features of the invention will be apparent from the following description taken in connection with the accompanying drawings in which—

Figure 1 is a side elevation of a rotary 25 shuttle embodying my invention; Fig. 2 is a section on line 2—2 of Fig. 1, with the bobbin and tension device shown in elevation; Fig. 3 is a view similar to Fig. 1 and showing certain parts in a different arrangement, and Fig. 4 is a perspective view 30 of the tension device.

Referring to the drawings 10 indicates the shuttle which is provided with a central post 11 for the bobbin 12. The shuttle has 35 inwardly projecting lugs 13 and 14 in which a pivot pin 15 is journaled. Secured to the pin 15 is an arm 16 arranged on the side of the shuttle and adapted to swing to and from a position over the bobbin. As shown 40 in Fig. 1 the arm 16 is in position to hold the bobbin in the shuttle and when in this position the beveled end 17 of the arm engages the under surface of a lug 18 on the outer end of the post 11. A leaf spring 19 45 is secured on the under side of the arm 16 and when the arm is in the position shown in Fig. 1 this spring holds the arm in engagement with the lug 18. When the arm 16 is swung to the position shown in Fig. 3 50 the bobbin 12 may be removed from the shuttle, the arm being held in this position by the engagement of the lateral extension 20 of the spring 19 with a recess 21 in the shuttle. The spring 19 is also provided with a

lateral extension 22 which serves as a thumb 55 piece to permit the spring to be disengaged from the recess 20.

A tension leaf 23 is provided with a pair of ears 24 which are journaled on the pivot 15 so that the leaf 23 may be swung on the 60 pivot independently of the arm 16. A spring 25, coiled about the pivot 15, has the end 26 thereof in engagement with the inner surface of the shuttle, the end 27 bearing against the leaf 23 and normally pressing 65 the leaf against the thread on the bobbin 12. The thread from the bobbin 12 leads through an opening 28 in the shuttle and the pressure of the leaf 23 on the thread produces a uniform tension therein irrespective 70 of the size of the thread or the amount of thread on the bobbin. It will be readily understood that when the bobbin is full of thread it will unwind much easier than when nearly empty because of the longer 75 moment-arm when the bobbin is full. The spring 25 is so arranged that the pressure of the leaf 23 on the thread is a maximum when the bobbin is full and therefore as the thread is withdrawn from the bobbin the 80 pressure of the plate on the thread decreases. In other words, the pressure of the leaf 23 on the thread varies directly with the amount of thread on the bobbin and thus compensates for the variation in tension due 85 to the decrease in the moment arm, as the bobbin is emptied.

When it is desired to remove the bobbin from the shuttle it is essential to swing the plate 23 from between the flanges of the 90 bobbin and in order to conveniently effect this a pin or arm 29 is secured to the pivot 15 and arranged to engage the leaf 23 and cause the latter to be swung away from the thread as the arm 16 is swung to the position shown in Fig. 3. When the leaf is thus swung from its operative position by the arm 16 the latter is under the influence of the spring 25 which tends to swing it back to the position shown in Fig. 1. The engagement of the extension 20 with the recess 21, however, holds the arm 16 against the pressure of the spring 25.

When the machine is running at high speed there is normally a tendency for the 105 large bobbin to overrun or unwind too much thread and the leaf 23, bearing on the thread, acts as a brake to prevent this.

Having thus described my invention, what I claim is:—

1. The combination with a shuttle, of a pivoted tension leaf adapted to contact with the thread on the bobbin and a helical torsion spring coaxial with the pivot of said leaf and having one end engaging the shuttle and the other end engaging the leaf and so arranged that the pressure of the leaf on the thread will vary directly with the distance of the leaf from the axis of the bobbin.
2. The combination with a shuttle, of a bobbin, a pivot, an arm secured to said pivot and adapted to hold said bobbin in position, and a spring-pressed leaf loosely arranged on said pivot and adapted to engage the thread on said bobbin, and means on said pivot adapted to engage said leaf and withdraw

the same from the thread when said arm is swung to release said bobbin.

3. The combination with a shuttle, of a bobbin, a pivot, an arm secured to said pivot and adapted to hold said bobbin in position, a spring-pressed leaf adapted to engage the thread on said bobbin, means whereby said leaf is withdrawn from operative position when said arm is moved to release said bobbin, and a spring on said arm adapted to engage said shuttle to hold said arm and leaf in inoperative positions.

In testimony whereof I affix my signature in presence of two witnesses.

RICHARD K. HOHMANN.
